UNITED STATES PATENT OFFICE.

JOHN KUKELL, OF PLEASANT CITY, OHIO.

RAILROAD-SWITCH.

1,333,622.

Specification of Letters Patent. Patented Mar. 16, 1920.

Application filed November 7, 1919. Serial No. 336,281.

To all whom it may concern:

Be it known that I, JOHN KUKELL, a citizen of Czechoslovakia, residing at Pleasant City, county of Guernsey, and State of Ohio, 5 have invented certain new and useful Improvements in Railroad-Switches, of which the following is a specification:

This invention has as its object the provision of means for automatically moving 10 the switch and mate points of a railroad in advance of an approaching train and for returning the same after the passage of the same.

A further object is to provide such means 15 in forms which may be operated manually from the track-side or from the train as may be preferred.

These objects are attained by the novel construction and combination of parts hereinafter described, and shown in the accompanying drawings, forming a material part 20 of this disclosure, and in which—

Figure 1 is a plan view showing a section of railway track including a switch and turnout and indicating the application of 25 the apparatus.

Fig. 2 is a side elevational view of the same.

Fig. 3 is a longitudinal sectional view 30 taken through one of the operating devices.

Fig. 4 is a similar view showing the mating device used cooperatively therewith, and

Fig. 5 is a plan view of Fig. 3, the cover being removed.

Referring to the drawings in detail, the 35 numeral 10 indicates an ordinary type of tie, upon which are mounted the running rails 11 and 12, the former being straight throughout, and the latter curved as at 14, concentric to which is a similar curved rail 13, terminating at the point 15, to which are pivotally attached the mate and switch points 16 and 17, the latter connecting between the rails 12 and 18.

The switch points 16 and 17, are connected near their front ends by a rigid bar 19.

Secured upon the ties 10, in advance of the switch point, are raised hollow casings 50 20, provided with partial covers 21, similar casings 22 being disposed beyond the switch point having covers 23, the upper portion of both these casings are beveled interiorly downward toward their thicker ends as at 55 24 and 25, and are provided with rack teeth

26 and 27, disposed transversely across their diagonal upper surface.

Engageable with these rack teeth are pinions 28 and 29, fixed upon spindles 30 and 31, which pass through elongated, oblique 60 slots 32 and 33, formed in the sides of the casing 20 and 22 in such manner as to guide the pinions maintaining them in contact with the recess 26 and 27.

A pair of arms 35 extend in the manner 65 of a fork from a head 36, obliquely upward and are provided with extensions 37, which project normally above the top of the casing through the opening or uncovered portion of the same.

Extending oppositely from the head 36 and horizontally are bars 38, having attenuated ends 39, terminating in forks 40, in which is a pivotally connected link 41, having heads 42, engaged with a bell-crank 75 lever arm 43 fulcrumed at 44, the other arm 45 of a bell-crank lever engaging with a pin 46.

In a similar manner, the forked arms 48 are engageable with the spindles 31, the 80 arms terminating in a head 49 provided with a raised portion 50, and extending from the head 49 is a bar 51 terminating in forked heads 52 in which is engaged a link 53, having a head 54, pivoted to the 85 bell-crank lever arm 55 pivoted on a pin 56 set in the tie, the opposite arm 57 of the bell crank lever engaging with the pin 46.

The pin 56 is fixed in a bar 58, passing below the track rails 11 and 14 and also below the switch points, and engaged with the bar 58, centrally between the running rails, by pins 59, is a projection 60, formed to the connecting bar 19.

Also pivotally engaged with the outer end 95 of the bar 58, by pins 61 is the inner end of bell-crank elements 62 pivoted upon the tie and having projecting arms 64, carrying a vertical bar 65, by which the switch point may be manually operated.

In operation, a train approaching the switch point has attached projections, indicated by the dotted line 66 adapted to make contact with the upper extending head 50 pressing it downward, and causing the 105 gear 29 to travel downward along the inside rack 27 which causes the arm 57 to be withdrawn into the casing 20, pressing the link 43 and turning the bell-crank levers so as to move the switch point outwardly. If a 110

train advancing the other direction, makes contact with the extending heads 37, causing the pinion 38 to move down the inclined rack 26, pressing the bar 39 forward, and transmitting movement to the link 41 of the bell-crank levers, the cross bar 58 is outwardly, carrying the switch points.

From the foregoing it will be seen that an effective train operating device has been disclosed, which may be moved by hand by properly manipulating the vertical bar 65 if it be so desired.

Having thus described my invention what I claim as new and desire to secure by Letters Patent, is—

1. In a railway track switch throwing device, the combination with a pair of track side casings open tops, and openings at adjacent ends thereof, of diagonally disposed racks arranged transversely in said casing, pinions operable in said racks, spindles movable in said casing to which said pinions are connected, forks embracing said pinions, heads extending through said casing engaged with said forks, bar connections opposite to said head in said fork, bell-crank levers pivoted adjacent to said track side, connections between said forks and said bell-crank levers whereby they are operated upon the depression of said heads, and operative connections between the opposite ends of said levers and said switch point whereby they may be moved to and fro upon depression of the said heads.

2. In a railway track switch, the combination with a pair of hollow casings disposed adjacent to the track side, transversely disposed rack teeth in said casings, arranged diagonally with respect thereto, gears operable in connection with said racks, forked elements adjacent to end of said gears, heads formed with said forked elements extending

upward through said casing and depressible therewithin, bars formed with said rack extending through openings in the opposite end of said casing, bell-crank levers pivoted adjacent to the rails of said trackway, link connections between said bars and said bell-crank levers, a bar connected with said bell-crank levers operative connections between said bar and the point of said switch whereby they may be moved according to the depression of either of said pairs of heads.

3. In a railway switch, the combination with a pair of hollow casings disposed adjacent to one of the track rails, forks movably engaged in said casing, gears upon which said forks are supported, obliquely disposed racks formed integral with said casings to which said gears are engaged, means for guiding said pinions in a diagonal path, forks arranged upon the sides of said gears and extending through the opening in said casing, heads formed with said forks adapted to make contact with the portion of a train passing thereover by which they may be depressed, bell-crank levers pivoted in opposed pairs adjacent to the side rails, connections between said heads and said bell-crank levers whereby they are operated in unison, a universal bar connected with the inner ends of said bell-crank levers, said universal bar passing below said track rails and switch point, a rigid bar connected between said switch point, connections between said universal bar and said rigid bar and means operatively engaged with the outer ends of said universal bar whereby said switch point may be manually operated.

In testimony whereof I have affixed my signature.

JOHN KUKELL.
